UNITED STATES PATENT OFFICE.

JOHN M. RATHMELL, OF CONNEAUT, OHIO, ASSIGNOR TO DUNN ROAD MACHINERY COMPANY, OF CONNEAUT, OHIO, A CORPORATION OF OHIO.

MACHINE FOR MAKING CONCRETE PAVEMENT.

Application filed January 12, 1921. Serial No. 436,722.

To all whom it may concern:

Be it known that I, JOHN M. RATHMELL, a citizen of the United States, residing at Conneaut, in the county of Ashtabula and State

5 of Ohio, have invented certain new and useful Improvements in Machines for Making Concrete Pavement; and I do hereby declare the following to be a full, clear, and exact description of the invention, such as 10 will enable others skilled in the art to which it appertains to make and use the same, reference being had to the accompanying drawings, and to the letters of reference marked thereon, forming part of this specification.

15 My invention relates to machines for making concrete pavements of the type shown and described in U. S. Letters Patent No. 1,265,499 issued to Allan J. Parrish, May 7, 1918.

20 The object of my invention is to provide in such a machine a vertical moveable strike-off plate which will strike off freshly laid concrete to the desired contour of the pavement, so that the said plate can be raised upwardly out of its working position to permit the machine to be moved backwards.

Another object of my invention is to provide a tamping device adjacent to the front surface of the strike off plate which will be 30 adapted to force the coarser particles of the aggregate deep enough below the surface of the mass of concrete so that said coarse particles will pass under the strike-off plate so that the surface of the concrete left by said 35 strike-off plate will not be scarred or grooved by said particles.

Another object of my invention is to provide lever actuated means to stop all of the tamping members of the machine in their 40 raised position, by means of a single lever, after the strike-off plate has been raised from its operative position. This and other features of my invention are hereinafter more fully described and pointed out and 45 are illustrated in the accompanying drawings in which:

Figure 1 is a plan view of a machine for making concrete pavements embodying my invention.

5) Figure 2 is a right hand elevation of the same.

Figure 3 is a transverse section on the line 3-3 in Fig. 1.

Figure 4 is a front elevation with portions thereof broken away.

55 Figure 5 is a side elevation of a fragment of the machine showing lever and latch mechanism for disengaging one of the power clutches.

Figure 6 is a front view of one of the 60 brackets for supporting the strike-off plate.

Figure 7 is a side view of the same.

Figure 8 is a transverse section of another 65 form of clearing tamper to be used in front of the strike-off plate.

Figure 9 is a front view of a fragment of the same with a portion thereof broken away.

In these drawings A A indicates the usual 70 side forms for the pavement, which are preferably U-shaped channel irons set on edge at each side of the proposed road-way or pavement, from which position they may be removed after the pavement has been completed. Upon these said forms is placed a 75 carriage comprised of end beams B B to which are secured the brackets B' of the wheels B², which wheels travel upon the side forms A A. The two end beams B B are secured together by the beams C C by 80 means of the brackets C' C' C' C', the said brackets C' being suspended under the beams B by means of bolts b so that the elevation of the beams C, with relation to the end beams B can be adjusted as desired, and 85 as described in the above mentioned Letters Patent.

The ends of the beams C are secured together by means of beams D D, as shown 90 and described in said patent; the beams C C and D D thus forming a frame, which is suspended under the end beams B B. Upon the beams C C I place supporting brackets E E (see Fig. 4) upon which are placed transverse beams E' E'. Upon these 95 beams E' is mounted a motor F for furnishing the power necessary for operating the machine. I also place upon the beams E' E' windlass mechanism F' which is provided with the usual drums F² F² to receive 100 cables f (see Fig. 1) which pass from said drums around pulleys f' which are secured

upon the beams D D and extend forwardly from said pulleys to suitable anchors (not shown), at the side of the proposed pavement; the said drums and cables being for 5 the purpose of moving the machine forward during its operation.

Between the beams C C is located a beam C² which is mid-way between the beams C C and parallel therewith (see Figs. 2 and 3). 10 Upon the front beams C and the intermediate beams C² is placed vertical frames G G G. Upon these frames G are mounted walking beams H H, from the ends of which walking beams tampers H' and H² are suspended by 15 means of adjustable rods being provided with nuts h' and springs h² below the walking beams, so that the pressure exerted by the walking beams H upon the tampers H' and H² will be cushioned by the springs h². The 20 tamper H' is preferably a thin plate which is adapted to force the gravel and broken stone downwardly in the mass of concrete, while the tamper H² is preferably flat on its under surface and adapted to give a 25 smooth surface to the concrete.

For operating the walking beam H I mount a shaft I in the frames G, and place on said shaft I a friction clutch mechanism I' which is provided with a sprocket wheel 30 I² from which a chain belt I³ extends to the driving pulley of the motor F. The clutch I' has the usual operating cone i which is operated by a lever i', so that when the cone i is forced toward the clutch mechanism I' 35 the shaft I is caused to rotate.

Upon the shaft I above the walking beams H, I place eccentrics J (see Fig. 3); and upon said eccentrics I place the usual bands and rods J', the lower ends of said eccentric 40 rods J' being pivotally connected to the walking beams H so that when the shaft I is rotated the walking beams H are thereby caused to oscillate.

Upon the shaft I is placed a sprocket 45 wheel K from which a chain belt K' extends over a sprocket wheel K² upon the driven shaft K³ of the windlass mechanism F', so that as the shaft I rotates, the driving mechanism of the drums F² is also actuated. The 50 drums F² are provided with clutch mechanism L L and operating levers L' so that the said drums F² can be independently operated as may be desired, in moving the machine around the corners of a proposed pavement. I also mount in the frames G another shaft M, the ends of which are mounted in brackets M' M' secured upon the beams D D.

Upon the ends of the shaft M are placed 60 small sprockets M² M² from which chain belts M³ extend forwardly and around sprocket wheels M⁴ on the axles of the front wheels B² of the machine. This shaft M is provided with clutch mechanism N, said 65 clutch being operated by the hand lever N',

rod N² and bell-crank lever N'. For rotating the shaft M, a chain belt O extends from a pulley on the shaft K² to the sprocket wheel n of the clutch N, so that when it is desired to move the machine backwardly, the clutches 70 L of the drums F² are released, and the lever N' is operated to force the cone of the clutch N toward said clutch, which causes the shaft M to revolve, and through the chain belts M³ to turn the front wheels B² of 75 the machine backwardly; the chain belts I³, K' and O being constantly in motion during the operation of the machine.

Upon the front beam C are secured brackets P (see Figs. 6 and 7) which brackets are 80 provided with slotted holes p. Upon the brackets P is secured a strike-off plate Q which is secured by means of bolts Q' which are slidably secured in the slotted holes p in the brackets P so that said strike-off plate 85 can be raised and lowered. For the purpose of raising the strike-off plate I mount offset bell-crank levers R in suitable supports upon the front beam C with a link-bar R' extending from one arm of said levers to the 90 pivot R² in the strike-off plate Q. The strike-off plate Q is formed so as to give the proper contour to the upper surface of the cement.

In front of the strike-off plate Q is suspended a vertically reciprocating tamper S, which, by means of link bars S', is suspended upon the bell-crank levers S², which levers are pivoted in suitable supports upon the front beam C. For the purpose of oscillating the bell-crank levers S², I mount a spur-gear T upon a stud post secured in the forms G. This spur gear is provided with a crank-pin T', upon which crank-pin a pitman T² is pivoted and extends, and is pivoted to the opposite end of the bell-crank levers S².

The pitman T² is provided with a cushioning spring t, so that if the clearing tamper plate S encounters an obstacle during its 110 downward movement, the spring t will be compressed and thus avoid the breaking of the machine. In order to give motion to the spur gear T pinions U are placed above the shaft I which intermesh with the spur gears 115 T, so that the rotation of the shaft I, which operates the tampers H' and H² as hereinbefore described, also causes the clearing tamper S to be forced downward into the cement mass, thereby forcing any large 120 pieces of broken stone or gravel downward sufficiently to pass the lower edge of the strike-off plate Q.

In front of the clearing tamper S, I suspend an auxiliary strike-off plate V by 125 means of brackets V' secured to the front beam C; the plate V being stiffened by means of the channel iron V². As the machine moves forward this auxiliary strike-off plate V clears the largest portion of the 130

surplus concrete away, so that the strike-off plate Q is relieved of a large part of the strain incident to striking the top surface of the concrete to the proper grade.

5 It may happen that it will be necessary to back the machine up a few feet and pass over the work a second time, in which case it becomes necessary to stop the machinery so that the tampers H' and H² and the clearing tamper S are in their clear position, i.e., so that they will clear the upper surface of the concrete. In order to accomplish this I have provided a compound lever mechanism (see Fig. 5) consisting of a shaft 2 which is supported in suitable brackets 3 and 4 which are secured upon the beams C and E'. Upon this shaft 2 is secured a cross arm 5 to the ends of which rods 6—6 are pivoted; the opposite ends of said rods being pivoted to the free ends of the bell-crank lever R R.

Upon the shaft 2 is secured a hand lever 7, a suitable segment 8 with notches in its periphery being secured upon the bracket 25 4, said lever 7 being provided with a spring latch mechanism 9 adapted to engage notches in the segment 8 to retain the lever in the positions to which it is moved. By throwing the lever 7 to the position shown in Fig. 4, the strike-off plate Q is raised sufficiently to clear the upper surface of the cement.

Upon the shaft 2 between the brackets 3 and 4 I place a tube 10. On one end of this tube 10 is secured a lever 11, and between the free end of the lever 11 and the lever 7 is pivoted a link bar 12 (see Figs. 4 and 5). On the opposite end of the tube 10 is another lever 13 to which a spring 14 is attached by means of an adjusting screw 40 15 (see Fig. 4), the opposite end of said spring being secured to an offset 16 on the lever 7. The bracket 3 is provided with a forwardly projecting bifurcated arm 17, which is parallel with and under the shaft 45 2. Within this bifurcated arm 17 is pivoted a latch bar 18 which has a downward projecting shoulder 19 adapted to be engaged by the upper edge of the clearing tamper S when the same is raised upwardly 50 as shown in Fig. 5. This latch 18 is provided with a spring 19^a which normally presses the rear end of the latch bar 18 downward.

Upon the tube 10 is secured a downwardly projecting arm 20 which has a beveled rear surface 21. This arm 20 engages the latch 18 and prevents the tube 10 from turning when the lever 7 is thrown over to the position shown in Fig. 4, and retains it immovable until the bell-crank levers S² raise the clearing tamper S to its highest position, which causes the clearing tamper S to engage the shoulder 19 of the latch-bar 18 and disengage the same from the arm 20, which releases the tube 10 to the action of the spring

14 so that the said spring will rotate the tube 10 and operate the small clutch lever i' to open the clutch I', thereby stopping the operation of all of the tamping mechanism of the machine.

The lever, N' is then operated to close the clutch N which causes the machine to move backward as hereinbefore described. Of course it is understood that before the machine can be moved backward the cable 75 clutches L have to be released, so that the drums F² will unwind as the machine moves backward. When the machine has been moved backward as far as desired, the reversing clutch N is opened and the lever 7 80 is thrown over to the opposite position thereof, said lever engaging the offset 22 on the lever 13, thereby causing the clutch lever i' to close the tamper clutch I' and the lever 7 at the same time operating the shaft 2 to 85 drop the strike-off plate Q again to its proper position; after which the machine is again ready to move forward.

In Figs. 8 and 9 I have shown a different form of clearing tamper, in which I provide a plate 23 to which downwardly projecting fingers or rods 24 are secured, which extend through openings in the channel iron V², the said plate 23 being provided with a vertical rib or flange 25 to which the link 90 bar 26 is pivoted, the opposite end of said link bar being pivoted to the bell-crank levers S² so that in operation the fingers 24 are given a vertical movement and are forced downwardly into the mass of concrete 95 so as to engage and push downward any large particles of broken stone or gravel which might engage the lower edge of the strike-off plate Q, and cause deep grooves to be made in the surface of the cement. 100

The operation of the mechanism shown in Figs. 8 and 9 is identical with the operation of the clearing tamper plate S shown in the other figs.

Having thus shown and described the 110 construction and operation of my invention, I do not desire to be limited to the exact form of mechanism which I have shown and described, as many modifications can be made therein without departing from the 115 scope of my invention. Therefore, what I claim as new and desire to secure by Letters Patent is:—

1. In a machine of the class described, a vertically moveable strike-off plate, manually operated lever mechanism to raise and lower said strike-off plate, and means to engage said lever mechanism and lock it against movement whereby said strike-off plate will be rigidly maintained at any desired elevation.

2. In a machine of the class described, a transverse beam, lever mechanism secured on said beam, a transverse strike-off plate suspended on said lever mechanism, a man-

ually operated lever, rods connected with said manually operated lever and said first mentioned levers, and latch mechanisms to lock said manually operated lever in the 5 desired position.

3. In a machine of the class described, a strike-off plate adapted to strike off a layer of plastic cement to the required thickness, a vertically reciprocating clearing tamper 10 suspended adjacent to and in front of said strike-off plate, and power driven mechanism adapted to force said clearing tamper downward into the cement and lift it out of the same.

15 4. In a machine of the class described, a vehicle, a strike-off plate mounted in the frame thereof, a vertically reciprocating clearing tamper adjacent to and in front of said strike-off plate, and motor, gear and lever mechanism to impart vertical reciprocation to said clearing tamper.

20 5. In a machine of the class described, a vehicle, a strike-off plate mounted in the frame thereof, a vertically reciprocating clearing tamper adjacent to and in front of said strike-off plate, bell-crank levers mounted in the frame of said vehicle, links pivoted to one arm of said levers and to said clearing tamper plate, and motor, gear and 25 pitman mechanism to oscillate said bell-crank lever whereby vertical reciprocations are imparted to said clearing tamper plate.

30 6. In a machine of the class described, a vehicle, a vertically moveable strike-off plate mounted on the vehicle frame, lever mechanism to raise and lower said strike-off plate, a stationary strike-off plate mounted in said vehicle frame, and suspended in front of said moveable strike-off 35 plate, the lower edge of said stationary strike-off being at a higher elevation than the lower edge of said moveable strike-off.

40 7. In a machine of the class described, a vehicle adapted to travel over a proposed pavement, a transverse beam in the frame of said vehicle, brackets secured on the front face of said beam having slotted holes therethrough, a strike-off plate, bolts passing through said plate and through said slotted 45 holes, lever mechanism adapted to raise and lower said strike-off plate, L-shaped brackets secured upon said beam and extending forwardly and downwardly in front of said moveable strike-off plate, and a stationary 50 strike-off plate secured on said brackets at a higher elevation than said moveable strike-off plate.

55 8. In a machine of the class described, a vehicle adapted to travel over a proposed pavement, a transverse beam in the frame of said machine, a vertically moveable strike-off plate supported on said beam, lever mechanism to raise and lower said strike-off plate, a vertically reciprocating clearing 60 tamper in front of said strike-off plate,

lever and gear mechanism adapted to impart vertical reciprocation to said clearing tamper, and a stationary strike-off plate supported upon said beam in front of said clearing tamper.

70 9. In a machine of the class described, a vehicle, a strike-off plate therein, a clearing tamper in front of said strike-off plate, bell-crank lever and link mechanism to support said clearing tamper, gear mechanism mounted in the vehicle frame, a pitman slidably pivoted to said bell-crank lever and to an eccentric pin on one of said gears, and spring cushion mechanism on said pitman adapted to cushion the forward thrust of 75 said pitman against said bell-crank lever, whereby the downward thrust of said clearing tamper is allowed to yield when unyielding obstacles are encountered.

80 10. In a machine of the class described, a vehicle frame, vertically moving tampers mounted therein, a vertically moveable strike-off plate, a vertically moving clearing tamper mounted therein, motor, gear and lever mechanism for operating said tamping 85 mechanisms, clutch mechanism adapted to be operated to stop and start said gear and lever mechanism, spring actuated lever mechanism adapted to close and release said clutch, latch mechanism adapted to be engaged and released by said clearing tamper to permit said spring actuated lever mechanism to open said clutch when the clearing 90 tamper has reached the end of its upward movement whereby the tampers will be stopped while clear of the finished surface 95 of the pavement, and manually operated lever mechanism adapted to raise said strike-off plate and put tension on the spring of said spring actuated lever mechanism.

100 11. In a lever mechanism for a machine of the class described, a shaft mounted in suitable brackets, a hand lever secured thereon, a cross-arm on the opposite end of said shaft, rods extending from the ends of said cross-arm to bell-crank levers which support a strike-off plate, a clutch operating lever mounted in the machine frame, a tube on said shaft, a lever on said tube, a link-bar connecting said lever and said clutch lever, 105 a bracket, a spring pressed latch pivoted in said bracket, a clearing tamper adapted to engage and operate said latch at the upper end of its stroke, a stop secured on said tube adapted to engage said latch and restrain 110 the rotation of said tube, an operating lever on said tube, a spring secured to said operating lever and to said hand lever, an off-set shoulder on said operating lever adapted to overlap said hand lever, whereby when said 115 hand lever is operated in one direction tension is put upon said springs so that the same will rotate said tube when the latch is released by the clearing tamper.

12. In a machine of the class described, a

plurality of vertically moving tamping devices, motor, gear and clutch mechanism for operating said devices, a vertically moveable strike-off plate, a manually operated lever mechanism for raising said strike-off plate, spring and lever mechanism for operating said clutch mechanism and latch mechanism positioned in the path of one of said vertically reciprocating tamping devices where-

by it may be engaged and operated by 10 said tamping device to release said spring and lever mechanisms to open said clutch mechanism when all of said tamping devices have been raised above the surface being tamped.

15

In testimony whereof I affix my signature,

JOHN M. RATHMELL.
